UNITED STATES PATENT OFFICE.

LESTER S. GUNDERMAN, OF PITTSBURGH, PENNSYLVANIA.

MECHANICAL TOY.

Application filed November 10, 1924. Serial No. 748,986.

To all whom it may concern:

Be it known that I, LESTER S. GUNDERMAN, a citizen of the United States, residing at 251 Kennedy Ave., Pittsburgh, in the county of Allegheny and State of Pennsylvania, have invented certain new and useful Improvements in Mechanical Toys, of which the following is a specification.

This invention is for a mechanical toy of the type in which a miniature vehicle is raised from a lower level to an elevated position from which it gravitates back to a lower level then through a loop and on to a still lower level at which it is stopped at the end of the tracks, mechanical means being provided for raising the vehicle from a lower level to a higher level.

The objects of the present invention are to provide a pleasing toy of simple mechanical construction, which is compact and may be cheaply manufactured.

The purpose is to provide a toy which will continue to operate automatically lifting a vehicle until it gravitates back to a low point.

To provide a structural track so adapted to have a cheap and durable construction and means whereby the ends of the sections of tracks are readily and securely connected.

Referring to the accompanying drawing in which:

Fig. 1 is a side view of the assembled toy, showing the parts in one position.

Fig. 2 is a plan view, the car being removed.

Fig. 3 is a part plan view of the hinge end of the tracks.

Fig. 4 is an end view of tracks showing the hinge pivots.

Fig. 5 is a plan of the hinge part.

Fig. 6 is a side view of the hinge.

Fig. 7 is a part section view of the track stop.

Referring to the drawing, 9 designates a rectangular base preferably of sheet steel material with downwardly turned edges. Secured to the base is a looped track 10 having slightly upturned ends 11 and 12 to which are secured hinges 13 and 14 by bolts or other means to minimize space in packing the toy for shipment, a pair of swinging tracks 15 and 16 are pivoted at 17 and 18 to the hinges 13 and 14. The tracks 10, 15, and

16 are preferably made of a thin strip of steel, their cross section being in a channel shape turned upwardly as shown in Fig. 4. One end of the tracks 15 and 16 have their ends bent outwardly towards each side forming a pair of pivots 17 and 18 as shown in Figs. 3 and 4.

The outward end portions 19 and 20 of the tracks 15 and 16 are bent downwardly for retarding the movement of the rolling object 21 until the tracks are raised high enough that enough energy is derived in its downward course on the tracks 15 and 16 to carry the object around the loop 10 and across the opposite track to the abutments or stops 22 which arrest the progress of the object and prevent the object from leaving the tracks when being elevated.

In the drawing the track 15 is shown in a downward position and the track 16 is shown in an upward or elevated position and the rolling object just leaving the end of the track. The tracks 15 and 16 are provided with a series of holes 23 for lessening the weight of track to be lifted by the motor 24 which is mounted on top of the looped track 10. The motor is not shown in detail but may be of any conventional design. Mounted on the motor shaft is a crank arm 25 carrying a pivot bearing 26 on the end thereof.

A pair of connecting bars 27 and 28 have one end provided with a bearing adapted to fit on pivot bearing 26 the other end of the connecting bar being provided with pivot bearings 29 and 30 which reside in the ends of brackets 31 and 32 the lower ends of the brackets are mounted to the under side of the tracks 15 and 16. The upper surface of the hinges 13 and 14 are provided with upwardly formed projecting tips which extend into slots in the looped track and prevents the ends of the track 15 and 16 from having a swaying motion.

The rolling object 21 may be constructed of any suitable wheeled design.

The operation of the top may now be described. Assuming that the rolling object 21 is in a position at the end of track 15 the motor rotates crank arm 25 in such a direction as to cause the connecting bar 27 to raise track 15 to such a position as shown by track 16 in Fig. 1. The connecting bar

28 has now caused track 16 to be lowered to the position as shown by track 15 in Fig. 1.

The car reaching the elevated position 5 will then roll down track 15 through loop 10 then to the end of track 16 when track 15 is lowered and track 16 is sufficiently elevated the car 21 will gravitate back to the position as when started and the cycle of operations will be repeated.

From the foregoing description, taken in connection with the accompanying drawing, the advantages of the construction and method of operation will be readily apparent to those skilled in the art to which the invention appertains, and while describing the principle of operation of the invention together with the device which is now considered to be the best embodiment thereof, it is to be understood that the device shown is merely illustrative and that various changes in the form, proportion and the minor details of construction may be resorted to without departing from the principle or scope of the claims.

I claim as my invention.

1. An automatic toy comprising a stationary loop and reversely incline tracks, and means for elevating the ends of one 30 track and alternately lowering the end of the opposite track, and an object adapted to travel on the tracks by gravity, elevating the end of one track serves to elevate the said object from whence it will roll through a loop to the end of the opposite track.

2. An automatic toy, comprising a looped track, a pair of tracks hinged at one end of each to the end of the center track its 40 opposite end being bent downwardly for retarding a rolling object, said tracks being so positioned that their free ends may be alternatively elevated and objects adapted to roll on said tracks by gravity.

3. An automatic toy, comprising a stationary looped track having a pair of tracks mounted at one end of each to the ends of the center track, said tracks being so positioned at each end that their outwardly extended ends may be alternatively elevated 50 and an object adapted to roll on said tracks by gravity.

4. An automatic toy, comprising a stationary center looped track, and end tracks hinged at one end of each to one end of the center track, the free ends of the said 55 end tracks being arranged to move higher than the center track, and a rolling object adapted to travel on said tracks and to be transferred from one end of one track to the opposite end of the other by gravity.

5. An automatic toy, comprising a stationary looped track, a pair of end tracks hinged at one end to one end of the looped track, the free ends of the said hinged tracks 65 being arranged to swing upwardly, and

power driven means for continuously raising and lowering the tracks alternatively during the operation of the toy, and a rolling object adapted to travel on the tracks by gravity and to be transferred from one track to the other by the lifting motion thereof.

6. An automatic toy, comprising a pair of tracks hinged at one end of each to a stationary looped track, means of alternatively elevating the ends of said pair of tracks in an upwardly direction and a traveling object arranged to roll in said tracks by gravity, the arrangement being such that the elevating of the hinged tracks elevates said object at the ends of said tracks along which it moves to the other end of said tracks, whence it is again elevated to return back to the opposite end.

7. An automatic toy comprising a pair of oppositely disposed, upwardly swinging tracks positioned at each end of a stationary looped track, means for swinging said tracks in an upwardly direction to alternatively elevate opposite ends, and an object to travel in the tracks by gravity, the said end tracks having their ends bent downwardly being arranged to retard the rolling object until a predetermined height is reached when said object rolls to the farthest end of the tracks, the upwardly swinging motion of said tracks serving to elevate said object for returning to the opposite position to be again elevated.

8. An automatic toy, comprising a pair of end tracks hinged to the end of a stationary looped track, means for positively elevating one end of said hinged tracks, and an object to travel on said tracks, connecting bars having one end pivoted on said end track, a crank pin engaging opposite ends of said connecting bars means for driving said crank pin, said crank pin and said connecting bars being arranged to raise and lower the tracks, and an object to roll from one track to the other by gravity.

9. An automatic toy, comprising a central looped track, a pair of tracks having one end of each hinged to the adjacent end of the looped track its opposite ends being arranged to alternatively swing upwardly and objects adapted to roll on said track, said hinged tracks having a portion of their outward ends bent downwardly to retard the backward movement of the said object when being elevated to the predetermined position from whence it gravitates to the opposite end of the opposite track and the upwardly swinging of the track returns the object to its initial position.

10. An automatic toy, comprising a stationary looped track, a pair of tracks hinged to the looped track in order that an object adapted to roll on said tracks may be received from one end of the end tracks to the opposite end of the end track and be

returned to the opposite end of said end track, one section of the end tracks near the ends thereof being bent downwardly and the ends of said tracks having their 5 ends bent upwardly, means for holding said object on the said tracks, a pair of connecting bars having one end of each pivoted on the said tracks, a crank pin engaging op-

posite ends of said connecting bars, means for driving said crank pin, said crank pin 10 and said connecting bar being arranged to raise and lower the pair of tracks, and an object to roll down one track to the other by gravity.

In testimony whereof I affix my signature.
LESTER S. GUNDERMAN.
